UNITED STATES PATENT OFFICE.

HENRY P. BENUS, OF KANSAS CITY, KANSAS.

SASH-LOCK.

1,150,412.

Specification of Letters Patent. Patented Aug. 17, 1915.

Application filed April 22, 1913. Serial No. 762,835.

To all whom it may concern:

Be it known that I, HENRY P. BENUS, a citizen of the United States, residing at Kansas City, in the county of Wyandotte and State of Kansas, have invented new and useful Improvements in Sash-Locks, of which the following is a specification.

This invention relates to sash locks, and particularly to locks for sashes of coaches, such as railway cars; and it has for its object the provision of a fastener of this character wherein the catch is mounted and constructed with a view to positively preventing the same from being accidentally disengaged from the keeper on the stop strip of the window casing.

The invention consists in the construction, combination and arrangement of devices hereinafter described and claimed.

20 In the accompanying drawings:—Figure 1 is a front view of the fastener, showing the application of the same to a sash; Fig. 2 is a rear view of the fastener removed from the sash and conventionally illustrating a receiving keeper for engaging the catch; and Fig. 3 is a view similar to Fig. 2, showing the catch in a released or retracted position.

The fastener comprises an attaching member 1 which is provided with right angularly extending branches 2 and 3, each having formed therein openings 4 for the reception of fastening screws whereby the device may be properly connected with two bars of the sash at one corner of the latter and at points beside the joint where the bars are connected together. This construction is desirable in that the attaching member forms a brace to prevent the bars of the sash at the corner from separating from each other. The branch 3 of the attaching member is provided with a casing portion 5 having an inner side wall 6 provided with a slot 7 and an outer side wall 8 having a relatively long slot therein and terminating at its upper end in a boss 10 and a stop shoulder 11. The back of the casing is open as indicated and extending preferably for the full depth of the casing, and immediately below the boss 10 is an integral pin 12 on which the upper end of a catch 12' is supported for swinging movements. The catch is provided with a relatively long detent 13 and a depending short arm 14, the latter having an integral angularly disposed branch 15 from which rises a stud 16. The

stud is embraced by one end of a projecting spring 17, the opposite end of the spring being confined in a recess 18 in the boss 10. The detent 13 is of a downwardly increased 60 width and its maximum length is projected through the slot 9 in the wall 8 by the action of the spring 17 and in such manner that the relatively long bottom surface 19 of the detent is wholly projected through the slot, 65 as clearly shown in Fig. 2.

The angle of the detent 13 with relation to the supporting pin of the catch is such that the detent is disposed wholly to one side of the vertical center of said supporting pin. This construction is necessary in order that the detent adjacent its connection with the supporting pin is brought into mutual contact with the sustaining shoulder 11 of the boss 10, thus bringing the strain 75 when the catch is supported upon the keeper to the shoulder and preventing an undue application of the strain to the supporting pin of the catch. The detent 13 is provided with a longitudinally curved inner surface 80 20, which is spaced from an adjacent curved inner surface 22 of the extension 14 so as to define therewith a slot 23 for the reception of a cam arm 24 of a releasing or retracting lever 25. The lever 25 is projected through 85 the slot 7 in the wall 6 of the casing 5 and is terminally provided with a relatively broad manipulating surface 26 which is superimposed with relation to a finger grip 27 which forms an integral part of the branch 90 2 of the attaching member 1. The lever also has a stop projection on its upper side, spaced from the inner end of the cam arm 24 and which engages the outer end of the branch 15 of the detent when said detent is 95 in engaged position, the spring 17 acting to move the detent to engaged position and causing the branch to exert camming action on the arm 24 and thereby turn the lever and raise its free end as shown in 100 Fig. 2.

The application of the fastener to the sash as clearly illustrated in Fig. 1 is such that when the sash is adjusted to an open position, the detent 13 will be advanced into 105 effective engagement with the keeper 28 on the stop strip of the window casing, the surface 19 at the bottom of the detent being in flat horizontal contact with the corresponding surface of the keeper 28. Through this construction it is evident that the detent 13 must be adjusted to a full retracted position

before the sash may be lowered. In order to effect proper retracted position of the catch the surface 26 of the retracting lever is pushed downwardly so as to cause the detent of the lever to engage against the surface 22 of the catch, moving the latter to a position where the surface 19 of the catch is disposed at a point substantially beneath the vertical center of the supporting pin of the catch. By arranging and constructing the parts as described it is seen that the catch is held in a reliable manner against becoming accidentally disconnected from the keeper 28 under vibratory movements of the sash. It is also seen that the catch is held against displacement from the keeper by the person whose weight may be incidentally applied to the sash.

From the foregoing description, taken in connection with the accompanying drawings, the construction and operation of the invention will be readily understood without requiring a more extended explanation.

Various changes in the form, proportion and the minor details of construction may be resorted to without departing from the

principle or sacrificing any of the advantages of this invention as claimed.

Having thus described my invention, what I claim is:—

A sash lock comprising a casing having a slot in its outer wall, a detent, having one end pivotally mounted in the casing and being thereby adapted to be turned outwardly through said slot, said detent having an arm at its pivoted end and spaced therefrom and provided with an inwardly extending branch, a spring bearing on said branch and serving to normally project the detent, and a lever pivotally mounted in the casing and having a cam arm to bear against the inner side of the detent and to enter the space between the detent and its branch arm, said lever also having a stop to engage the inner end of the branch when the detent is projected.

In testimony whereof I affix my signature in presence of two witnesses.

HENRY P. BENUS.
